UNITED STATES PATENT OFFICE.

THOMAS H. MACDONALD, OF BRIDGEPORT, CONNECTICUT, ASSIGNOR TO
THE AMERICAN GRAPHOPHONE COMPANY, OF WEST VIRGINIA.

COIN-CONTROLLED GRAPHOPHONE.

SPECIFICATION forming part of Letters Patent No. 621,834, dated March 28, 1899.

Application filed October 31, 1898. Serial No. 695,046. (No model.)

To all whom it may concern:

Be it known that I, THOMAS H. MACDONALD, a resident of Bridgeport, Connecticut, have invented a new and useful Improvement in Coin-5 Controlled Graphophones, which invention is fully set forth in the following specification.

My invention relates to coin - controlled graphophones, and is herein described as applied to the well - known spring - actuated 10 graphophone. It provides means for locking the spring-motor against winding until the proper coin has been dropped into the slot, for throwing the reproducer into contact with the sound-record and the partial nut of the 15 carrier into engagement with the feed-screw, for holding these parts in position while the sound-record is being reproduced, for disengaging them at the end of the performance, for returning the parts to their initial positions, and for other purposes hereinafter 20 described.

In United States Patent No. 582,754, granted to me May 18, 1897, I have shown a coin-controlled graphophone which accomplishes most 25 of the results above mentioned, and the invention embodied in the present application is an improvement thereon, whereby the construction is greatly simplified and the cost of manufacture much reduced.

30 In the drawings forming a part of this specification I have illustrated one form which my invention may assume, in which drawings—

Figure 1 is a plan, and Fig. 2 a front elevation, of my invention as applied to the well-known spring-actuated graphophone. Fig. 3 is a detail view showing the coin-lever and lock mechanism. Fig. 4 is a perspective of a section taken on the line 4-4 of Figs. 1 and 2; and Figs. 5 and 6 are end elevations on the 35 same section-line, showing the parts in operative and inoperative positions, respectively.

In the figures, in which like letters refer to like parts throughout, A is the base-plate, which is fastened to a wooden base, forming 40 the bottom of the inclosing box. (Not shown.)

A', A², A³, A⁴, and A⁵ are vertical bearing-plates secured to the base A, and B is the winding-shaft, turning in bearing-plates A' 45 A⁵ and supported at its outer end by the bearing B' and carrying at the other end, next to the bearing-plate A', the gear-wheel B², which

in turn engages gear-wheel B² on the shaft that carries the spring, as will be clearly understood. Situated on the extreme end of the shaft B, beyond A', is the ratchet C. 55

D is the coin-lever, pivoted at d on A' and so weighted that its nose drops into engagement with the ratchet C, thus locking shaft B against winding. The other end of lever D is carried back beneath the opening of the 60 coin-chute x and is in the shape of a horizontal forked plate, the space between the arms of the fork being narrow enough to arrest the coin and hold it without passing. A stud a' is mounted on plate A' and projects outward between ratchet C and the forward end of lever D. Levers E and F are pivoted on this stud, the former having a hook e, normally extending slightly above the stud d' on the lever d. The lower end of lever E lies against 65 an inturned flange f, projecting from the rear of lever F. When the coin is dropped into the slot and passes through the chute, it strikes at each side the arms of the fork, and thereby overbalances the forward end of lever 70 D and raises its nose from engagement with the ratchet C. The coin is not at this time allowed to pass off the lever, as the latter is held against its extreme tipping movement by the engagement of hook e with stud d'. 75

While the coin remains on the lever the latter cannot engage the ratchet C and the machine may be wound. When the machine begins to run, however, a stud c on the face of the ratchet-wheel C strikes against the 80 rear of the lever F and pushes it out of the way, and as flange f on lever F engages lever E it carries the latter, with the lever F, in its swing. The result of this is that hook e is freed from the stud d' and the weight of the 85 coin depresses the lever D till the coin drops therefrom, thereby permitting the nose of lever D to again engage the ratchet C. This position of the lever D does not interfere with the further rotation of the ratchet in the 90 operation of the machine, but will prevent any winding action without first introducing another coin. It is to be observed that while the spring is being wound stud c strikes against the front of lever F and pushes it 95 out of the way without disturbing lever E.

The reproducer is mounted upon a carrier

that is driven along the feed-screw by means of a partial nut in the usual manner and has a rearwardly-extending shifting-lever G for throwing the reproducer and the nut into and 5 out of engagement with the sound-record and feed-screw, respectively.

II is a bar or bail pivoted at h h to the bearing-plates A' and A⁵. The main portion of the bar or bail is trough-shaped and fits 10 around the end of the shifting-lever G, so as to have sliding engagement therewith. When the bail II is in its lower position, the reproducer is lifted away from the record and the nut from the feed-screw; but when the bail 15 is lifted it throws these parts into operative engagement in the well-known manner. A spring II', located in the trough of the bail, serves to retract the carriage, with the reproducer, to its initial position when the nut is 20 released from the feed-screw.

Sound is conveyed from the reproducer through a flexible tube I, which passes rearward over the sound-record, as shown, and has a telescopic engagement with a collar 25 free to turn on a standard J. The upper portion of J is hollow and communicates by means of an opening in its side with the tube i. The end of standard J projects through the boxing that incloses the machine and carries the horn or tube. (Not shown.)

Referring to the mechanism for operating the bail II, L (see Figs. 2 and 4) is a stud on the outer side of bearing-plate A⁵, upon which turns a large toothed wheel M and a catch-lever N. The upper end of N is offset above 35 M, so as to lie in the same plane with and rest against the arm of bail II. Projecting down from the arm of the bail II is trigger-lever h³, which lies between bearing-plate A⁵ and 40 wheel M. On M are two studs m m', the latter projecting on both sides of the wheel M. Fast in plate A⁵ is a cross-bar O, at each end of which is a coiled spring, one, P, being connected to N and the other, P', to H. A tooth b 45 is set in winding-shaft B, so as to engage the teeth of wheel M and turn the same one tooth at each revolution of the shaft B.

The operation of the parts is as follows: While the machine is being wound up each 50 revolution of the shaft B turns wheel M, through tooth b, one tooth forward in the direction indicated by the arrow. In the course of winding the inner end of the pin m strikes against the end of the trigger-lever h³ and 55 pushes it forward, moving it out of the way of the nose of the catch-lever N against a stop-pin a⁵ on bearing-plate A⁵, thereby lifting bail II against the action of the spring P'. Spring P simultaneously pulls catch-lever N forward, so that its hook n engages 60 with nose h², thereby holding the bail in elevated position, so as to throw the reproducer and nut into operative positions. The stop-pin a⁵ limits the play of the bail II and prevents 65 the spring of the motor from being wound beyond the point desired. When the operator has finished winding and released

the handle of the winding, crank-wheel M is turned by shaft B in the opposite direction, and in the course of its revolutions the other 70 pin m' strikes against the shoulder n' on catch-lever N, disengaging the catch-hook n from the nose h² on bail II, whereupon the latter, aided by spring P', falls, and thus lifts reproducer from the record and disengages 75 the partial nut from the screw, thus permitting spring II' to pull the carriage back to its initial position. A leather washer G' may be used as a buffer to prevent shock when the spring thus returns the carriage. Further 80 running of the machine is prevented by the inner end of pin m' bearing against stop-pin a⁵.

It will of course be understood that the various parts are so proportioned that during the time necessary to reproduce a complete 85 record (while the reproducer is borne by the carriage from one end of the sound-record to the other) wheel M revolves just far enough to carry it from the position where m lies against h³ to where m' strikes n'.

To prevent wrenching the parts or breaking a cog when the winding mechanism is locked or fully wound up, I provide a friction-clutch between the crank and winding-shaft. A barrel R is fitted to one end of the winding-shaft B by means of a slot therein engaging a pin r on the shaft and has fixed thereon the plates or disks R', while disks S, having prolongations that carry the handle T, are interposed between them, having only frictional 100 engagement therewith, the amount of friction being controlled by the screw R². It will be understood that the frictional engagement is so regulated that there is no relative movement between the parts of the clutch during 105 the normal winding action of the crank, but that when any unusual resistance is encountered, as when the spring is fully wound up or locked, the clutch slips, and thus prevents breakage.

Having thus described my invention, what I claim is—

1. In a coin-controlled graphophone the combination of a pivoted controlling-bar whose movements throw the reproducer into 115 and out of operative position, a toothed wheel having a projecting lug engaging an arm on said controlling-bar at one point in the revolution of said wheel, whereby the bar is tilted to throw the reproducer into operative position, a stop limiting the throw of said bar, a winding-shaft having a tooth thereon engaging said toothed wheel, a ratchet-wheel on said shaft, a lug projecting therefrom, a pawl-lever having a nose on one end engaging said 120 ratchet and the other end in proximity to a coin-chute, a pin on said pawl-lever, a pivoted lever engaging said pin and limiting the tilting movement of the pawl-lever and having a part depending in the path of the pin on the ratchet-wheel, substantially as described.

2. In a coin-controlled graphophone the combination of a driving-spring, a winding-shaft therefor, a ratchet-wheel thereon, a tilt-

ing coin-lever having a pawl-nose engaging said ratchet-wheel, a pivoted bar whose movements throw the reproducer of the graphophone into or out of operative position, means 5 limiting the tilting movement of the bar in either direction, a toothed wheel having a projecting lug engaging a depending arm on said bar at one point in the revolution of said wheel, a catch holding said bar in position for 10 the reproducer to operate, means on said toothed wheel tripping said catch before the wheel makes a complete revolution, a tooth on the winding-shaft engaging said toothed wheel, and means limiting the turning movement of said wheel in either direction, substantially as described.

3. In a coin - controlled graphophone the combination of a driving-spring, a winding-shaft therefor, a coin-operated lever controlling 20 the winding movement thereof, a pivoted bar throwing the reproducer of the graphophone into and out of operative position, a catch for engaging and holding said bar in operative position, a toothed wheel having a 25 lug for engaging an arm or lever on said bar to throw the latter into operative position, a lug on said wheel tripping said catch during the reverse revolution of the wheel, and a tooth on the winding - shaft engaging said 30 wheel, substantially as described.

4. In a coin - controlled graphophone the combination of a winding-shaft, a pivoted bar throwing the reproducer of the graphophone into and out of operative position, a toothed

wheel having a lug engaging and throwing 35 said bar into operative position during the winding, a catch engaging and retaining the bar in said position, a lug on said toothed wheel tripping said catch during the reverse movement of the wheel, and a tooth on the 40 winding-shaft engaging said toothed wheel, substantially as described.

5. In a coin - controlled graphophone the combination of a driving-spring, a winding-shaft therefor, and coin-controlled devices 45 normally locking the same against winding, with means limiting the winding and unwinding of the spring, a catch retaining the reproducer in operative position and means operated by the winding-shaft during its unwinding movement to trip said catch, substantially as described.

6. In a coin - controlled graphophone the combination of a driving-spring, a winding-shaft therefor, a ratchet-wheel on said shaft, 55 a pawl-lever having one end in proximity to a coin-chute and a nose on the other end engaging said ratchet-wheel, a stop in position to limit the tilting action of the pawl-lever, and tripping means on the ratchet-wheel to 60 free said lever, substantially as described.

In testimony whereof I have signed this specification in the presence of two subscribing witnesses.

THOMAS H. MACDONALD.
